UNITED STATES PATENT OFFICE.

WOLDEMAR DRÜHL, OF RIGA, RUSSIA.

STEAM-RAM.

SPECIFICATION forming part of Letters Patent No. 613,977, dated November 8, 1898.

Application filed November 1, 1897. Serial No. 656,994. (No model.)

To all whom it may concern:

Be it known that I, WOLDEMAR DRÜHL, a subject of the Czar of Russia, residing at Riga, Russia, have invented certain new and useful Improvements in or Relating to Pile-Drivers and the Like, of which the following is a specification.

My invention relates to a novel construction in a pile-driver, the object being to provide a simple, durable, and efficient device of this character; and it consists in the features of construction and combinations of parts hereinafter fully described and claimed.

In the accompanying drawings, illustrating my invention, Figure 1 is a rear elevation of the block or driver, showing the releasing-lever locked. Fig. 2 is a similar elevation showing the releasing-lever released. Fig. 3 is a sectional view on the line 3 3 of Fig. 1 and showing the releasing-lever released. Fig. 4 is a side elevation of the car and vertical guides in which said block moves.

Referring now to said drawings, B indicates a block provided on its sides with guide-lugs 1, adapted to enter guide-recesses in the parallel uprights a^2 , mounted on the car 2. Said car 2 preferably carries a boiler 3 and engine A, which latter drives the chain-pulley a' at the lower ends of said uprights a^2 , over which and a similar pulley a' at the upper ends of said uprights a^2 a flat-linked chain a is trained which is driven continuously in one direction. Said chain runs on one side, preferably midway between said uprights or guides a^2 , and is adapted to engage devices on said block B to raise the latter, as hereinafter described. A recess 4 is provided in said block B, in the top and rear faces of same, which is crossed transversely by a shaft c , which carries the sleeve d , provided with the arms d' and d^2 . Said arm d' is adapted to be engaged by the chain a , while said arm d^2 is connected with the upper end of a plunger mounted in a vertical opening 5 in said block B, extending from said recess 4 to the bottom of said block. Said plunger consists of two members g and i , having a spring h interposed between them to act as a cushion. The lower end i' of the member i is reduced in size and projects downwardly below the lower face of the block B, at about the center thereof. Said recess 4 is extended

downwardly on the rear face of the block B and in such extension receives devices for locking the arm d' in the position shown in dotted lines in Fig. 3, in which position it is engaged by the chain a . Said devices consist of two bars $e e$, fulcrumed on the shaft f and provided adjacent their upper ends with shoulders $e' e'$, which are adapted to engage the upper face of the arm d' to hold same in the position shown in dotted lines in Fig. 3. Said bars $e e$ are held at the inner limits of their movement and in engagement with said arm d' by means of the flat springs $e^2 e^2$, interposed between the outer faces of said bars and the inner faces of said recess. A wedge k' , mounted upon the end of and normally held at the upper limit of its movement by a spring k , normally rests with its sharp end in vertical alinement with the line of contact between the inner faces of the upper portions of the bars $e e$, so that by bearing on said wedge k' the same would force said bars $e e$ apart, and thus release the arm d' , and immediately upon release of the pressure would resume the position shown in Fig. 1. As said block B drops, the parts mounted thereon are in the position shown in Fig. 3. As it strikes the pile the portion i of the plunger is obviously forced upward and through the medium of the spring h the portion g thereof likewise, thus turning the sleeve d to the position shown in dotted lines in Fig. 3, when the bars $e e$ spring into the position shown in Fig. 1, thus holding said arm d' in position. Said arm d' thus projects into the path of the cross-pins b of the chain a , one of which engages said arm and raises it until the wedge k' comes into contact with and is depressed by the beam l at the upper ends of said uprights a^2 , when it spreads the bars $e e$, and thus releases the arm d' , which immediately turns out of the path of said chain a , thus permitting the block to drop.

I claim as my invention—

1. In a pile-driver, the combination with an endless chain moving vertically between upright guides, of a block movable between said guides and provided with devices adapted to engage said chain and devices for releasing it from such engagement, said devices comprising a lever pivotally mounted in said block and adapted to be swung into engagement

with said chain, a spring-actuated lock adapted to engage said arm to lock same into engagement with said chain, and a member adapted to release said lock when said block reaches the upper limit of its movement, whereby said arm will be released from engagement with said chain to permit said block to drop, substantially as described.

2. In a pile-driver, the combination with an endless chain moving vertically between upright guides, of a block movable between said guides and provided with devices adapted to engage said chain and devices for releasing it from such engagement, said devices comprising a lever pivotally mounted in said block and adapted to be swung into engagement with said chain, a spring-actuated lock adapted to engage said arm to lock same into engagement with said chain, and a member adapted to release said lock when said block reaches the upper limit of its movement, said member comprising a wedge adapted to be depressed by contact with a cross-beam between said upright guides to force said locking mechanism out of the path of said arm, whereby said arm will be released from engagement

with said chain to permit said block to drop, substantially as described.

3. In a pile-driver, the combination with an endless chain moving vertically between upright guides, and a cross-beam between said guides, of a block movable in said guides and provided with an arm pivotally mounted thereon adapted to engage said chain to raise said block, a spring-actuated lock adapted to spring into the path of said arm to lock same into engagement with said chain, a releasing-wedge adapted to be depressed by said cross-beam to release said lock and thereby said arm to permit said block to drop, a plunger connected with said arm and projecting below said block adapted to strike the pile and be forced upwardly to throw said arm into the path of said chain to again raise said block, substantially as described.

In witness whereof I have hereunto set my signature in the presence of two subscribing witnesses.

WOLDEMAR DRÜHL.
